UNITED STATES PATENT OFFICE

VICTOR R. DESPARD, OF VALPARAISO, INDIANA, ASSIGNOR TO MCGILL MANUFACTURING COMPANY, OF VALPARAISO, INDIANA, A CORPORATION OF INDIANA

SWITCH MECHANISM

Application filed August 2, 1926. Serial No. 126,689.

My invention relates to electric switch mechanisms and has for its object the provision of a switch mechanism which is adapted to effect the control of a plurality of circuits. 5 More specifically, my invention is an improvement over my copending application Serial No. 62,833, filed October 16, 1925, Patent No. 1,669,372. In my said copending application I set forth a switch structure in 10 which a pair of movable switch contacts, insulated one from the other, are adapted to effect a plurality of circuit changes. In that particular application, the switch mechanism is designed to bring about a series parallel 15 switching arrangement between a source of current supply and a plurality of translating devices. In constructing a switch mechanism of that character I find it difficult to bring about the most effective circuit connection at 20 all times between the movable switch elements and the stationary switch element. This is due primarily to the fact that the movable switch elements are fixedly mounted upon a carrier and for this reason effective 25 contact is sometimes difficult to obtain because four connecting portions of the two movable contacts are required to make a circuit connection at the same time. This difficulty is due to the fact that either the stationary contacts or the movable contacts are 30 not at the proper level. It is impossible to bring about an absolutely perfect alignment of the parts in actual practice and this would be necessary in order to have a four-point element in condition to make perfect contact at 35 the four contact points or surfaces at one and the same time.

My invention is designed to overcome this 40 objectionable feature by providing a structure in which the contacts between the parts are at all times insured without the necessity of such extreme accuracy in the manufacture. My present invention, while overcoming this 45 objectionable feature is, of course, not limited in its scope to the limitation of this objectionable feature merely in switches or devices of the kind specified herein or in my copending application but has obviously a wider application.

50 I will describe one form which my inven-

tion may take by referring to the accompanying drawing in which—

Fig. 1 is a sectional view of a switch structure constructed in accordance with my invention;

Fig. 2 is a sectional view on line 2—2 of Fig. 1;

Fig. 3 is an enlarged developed view of the runway for the movable switch element;

Fig. 4 is a fragmentary sectional view on 60 line 4 of Fig. 1;

Fig. 5 is a perspective view of the movable circuit elements and their carrier; and

Fig. 6 is a sectional view along line 6—6 of Fig. 5.

In these figures, I have illustrated my invention as applied to a switch of the character set forth in my said copending application without, of course, intending thereby to limit the scope of my invention. This switch is designed so that two movable contact elements 10 and 11 may effect various circuit interconnections between a plurality of contacts such as the contacts 13 and 14, and the like mounted in a suitable circular runway 75 15. The arrangement is such that the contact making elements 16 and 17 of the switch element 10 and the contact making portions 18 and 19 of the switch element 11 ride over these stationary contact elements such as the 80 elements 13 and 14 in the direction of the arrow as shown in Fig. 3. It will be apparent that the contact making portions 16, 17, 18 and 19 may ride upon one element 14 for instance, and then drop by snap action over 85 the top portion of the element 14 onto the lower portions of the element 13.

Suitable means are provided on rotating the carrier 12, these means having recoil mechanism so that the reverse rotation of the carrier 12 is prevented. It will be apparent that it is necessary, under certain conditions of circuit closure, that all of the parts 16, 17, 18 and 19 make contact at one and the same time and in order to insure such contact I 90 loosely mount the contact elements 10 and 11 upon their carrier 12. This I do by providing holes in the switch elements 10 and 11, such as the hole 20, corresponding to the hole 21 in the carrier 12. I then fasten the two 95 100

parts together loosely as for instance by the metallic loop 22, which is threaded through the holes and is then bent into shape to hold the parts to that degree of security which is necessary while still permitting an adjustment of the corresponding switch element so that it may accommodate itself properly to engage the contact segments such as the segments 13 and 24.

10 I have given the reference numerals 23, 24, 25 and 26 to the remaining contact segments which are placed about the runway 15. It will be seen that by virtue of this construction and mounting of the switch element that I am at 15 all times assured of adequate contact between the corresponding switch element such as the switch element 10 or the switch element 11 and the cooperating contact segments with which it may at any particular time be de- 20 signed to be in contact. The carrier 12 may occupy six different positions as illustrated, there being six resting points along the runway 15 as will be clear from inspection of Figs. 2 and 3. The carrier 12 loosely lies 25 within the casing 27 for the switch with the exception that it is acted upon by a finger piece 28 fitting into the hole 29 through the agency of which the said carrier 12 is rotated, the hole 29, as is more clearly apparent from 30 Figs. 2 and 5, flares toward both extremities toward its center so that the finger 28 may adjust itself in a slight angular manner within said hole without thereby moving the carrier 12.

35 The carrier 12 is further pressed into its lowermost position by a spring 29, which spring presses against a washer 30 interposed between said spring and the carrier 12. The finger 28 is controlled by the rotatable man- 40 ually controlled finger piece 31 suitably held in position on the finger 28 by the screw 32. The finger 28 has a shoulder 33 and said fin- ger also has a slot 34 in which a pawl 35 rides, this pawl being integral with a loosely mount- 45 ed collar 36 slidable along the circular upper portion of the finger 28. The pawl rides in the slot 34 and the free extremity of the spring 29 presses against the collar 36, thus pressing the pawl 35 to the right (Fig. 1).

50 The finger piece 31 has a pair of slots which engage the pawls 35 to move it in a clockwise direction, but the pawl having the inclined surface will not move should the finger piece 31 be moved in a counterclockwise direction 55 as it is pressed to the left against the action of the spring 29. The carrier 12 is therefore moved only in the direction of rotation, the ratchet mechanism just described preventing 60 the finger piece 31 from rotating in the op- posite direction.

From what has been described, the nature of my invention will be readily apparent to those skilled in the art and having thus de- 65 scribed one form which my invention may

take, what I claim as new and desire to secure by Letters Patent is:

1. A device of the character described comprising a plurality of relatively stationary contacts, a pair of relatively movable bridging contacting elements, each of said elements being adapted to at times establish contact between two of said contacts and both of said elements adapted to engage all of said contacts, a single carrier for said elements, and means for loosely positioning said elements upon said carrier so as to permit rocking movement therebetween. 75

2. A device of the character described comprising a plurality of relatively stationary contacts, a pair of relatively movable bridging contacting elements, each of said elements being adapted to at times establish contact between two of said contacts, a single carrier for said elements, means for loosely positioning said elements upon said carrier, means for actuating said carrier, and a ratchet interposed between said last aforesaid means and said carrier. 80 85

3. A device of the character described comprising a plurality of relatively stationary contacts arranged in a circular path, a pair of relatively rotatable bridging contacting elements, each of said elements being adapted to at times establish contact between two of said contacts, a single carrier for said elements, means for loosely positioning said elements upon said carrier, means for actuating said carrier, and a ratchet interposed between said last aforesaid means and said carrier. 90 95 100

4. A device of the character described comprising a plurality of relatively stationary contacts, a pair of relatively movable bridging contacting elements, each of said elements being adapted to at times establish contact between two of said contacts, a single carrier for said elements, and a clamping ring for loosely positioning said elements upon said carrier. 105 110

5. A device of the character described comprising a plurality of relatively stationary contacts arranged in a circular path, a pair of relatively rotatable bridging contacting elements, each of said elements being adapted to at times establish contact between two of said contacts, a single carrier for said elements, and a clamping ring for loosely positioning said elements upon said carrier. 115 120

6. A device of the character described comprising a plurality of relatively stationary contacts, a pair of relatively movable bridging contacting elements, each of said elements being adapted to at times establish contact between two of said contacts, a single carrier for said elements, a clamping ring for loosely positioning said elements upon said carrier, means for actuating said carrier, and a ratchet interposed between said last aforesaid means and said carrier. 125 130

7. A device of the character described comprising a plurality of relatively stationary contacts arranged in a circular path, a pair of relatively rotatable bridging contacting elements, each of said elements being adapted to at times establish contact between two of said contacts, a single carrier for said element, a clamping ring for loosely positioning said elements upon said carrier, means for actuating said carrier, and a ratchet interposed between said last aforesaid means and said carrier.
